UNITED STATES PATENT OFFICE.

WILLIAM HUMPHREY BUTTRAM, OF SALLISAW, OKLAHOMA, ASSIGNOR OF ONE-HALF TO R. KOBEL, ONE-FOURTH TO W. D. MAYO, AND ONE-FOURTH TO J. M. MAYO, ALL OF SALLISAW, OKLAHOMA.

RIM TOOL.

1,420,813.

Specification of Letters Patent. Patented June 27, 1922.

Application filed June 8, 1921. Serial No. 475,940.

To all whom it may concern:

Be it known that I, WILLIAM HUMPHREY BUTTRAM, a citizen of the United States, residing at Sallisaw, in the county of Se-
5 quoyah and State of Oklahoma, have invented certain new and useful Improvements in a Rim Tool, of which the following is a specification.

10 My invention relates to automobile appliances and in particular to a tool adapted to be used for the contraction and expansion of demountable rims.

15 The particular object of the invention is to provide a tool of this character which may be readily applied or detached from a rim, and one which is designed to be applied to any size of rim, in such a manner that the rim may be expanded or contracted with the minimum amount of energy on the 20 part of the operator.

A further object of the invention is to provide a tool of this character which is self-centering within the rim, and which is positive in its action relative to the engagement of the rim.

25 With these and such other objects in view as will be apparent from the description, my invention resides in the novel construction, combination and arrangement 30 of parts hereinafter described and claimed, and taken in connection with the accompanying drawings, in which—

Figure 1 is an elevation illustrating the tool as applied to a rim;

35 Figure 2, a vertical section through the rim and tool as applied;

Figure 3, a detailed elevation of a modified element of the tool; and

40 Figure 4, a detailed perspective of an element employed.

Figure 1 illustrates the preferred embodiment of my invention as applied to a rim 1 carrying the usual tire 2. In detail, the tool comprises the screw threaded shaft 3 45 having an eye 4 at one end in which is positioned an operating lever 5. Cross blocks 6 are provided to engage over the shaft 3 at opposite ends thereof, being provided with central apertures internally 50 screw-threaded to engage the shaft. These blocks are two in number and the outer ends of the cross arms are bifurcated to receive therein rods 7 and 8, pivoted between the bifurcations by means of pivot pins 9 55 and 10.

The arms 7 are arranged in pairs extending from opposite sides of the blocks 6, and are pivoted at their outer ends between the pairs of U-shaped metal castings 11, which castings are held connected by means of the 60 pivot pin 12 of the arms. The castings 11 are of such dimensions as to extend, when applied to a rim, upwardly along the sides of the rim, as best illustrated in Figure 2. The ends of the castings are provided with 65 a series of aligned perforations 13 in which pivot studs 14, carried by hook members 15, are adapted to be adjustably engaged, whereby the hook members are pivoted in the castings in such manner as to be engaged between the rim and the tire, as illustrated in Figure 2.

Each pair of arms 8 is pivoted at the outer ends of the arms in a similar manner, to substantially rectangular castings 16 75 adapted to bear against the inner surface of the rim when the tool is applied. The disposition of the cross blocks, arms and castings is such that when the tool is applied to the rim the shaft 3 will be centrally 80 positioned within the interior of the rim, and upon operation of the lever 5 the blocks 6 may be drawn towards or away from each other to contract or expand the respective pairs of arms 7 and 8. As illustrated 85 in Figure 2, the opposite ends of shaft 3 are reversely threaded for an obvious purpose, but if desired only one end of the shaft may be threaded, namely, the outer end, and the inner block 6 may be held in 90 position on the shaft by means of collars 17 arranged at opposite sides thereof, as illustrated in Figure 3.

In operation, the tool is placed within a rim and the handle 5 turned to draw the 95 blocks 6 toward each other a sufficient distance to bring the castings 16 and 11 into engagement with the interior of the rim, whereupon hooks 15 are engaged over the rim as described, and upon manipulation 100 of the lever 5 in the proper direction the blocks 6 are moved away from each other, contracting the arms 7 and 8 and drawing the rim sections inwardly, as illustrated in Figure 1. In order to expand the rim, 105 it is simply necessary to reverse the direction of movement of the lever 5, in which instance the castings or lugs will expand against the rim and force the same outwardly into its proper engagement. 110

While I have described and illustrated certain details of construction in this preferred form of my invention, I desire it to be understood that I do not intend to limit 5 myself to these, but that any such may be used as will fall within the scope of the invention as claimed.

I claim:

10 A rim tool of the character described comprising a central member adapted for rotation, a pair of cross blocks on said member, radially disposed arms extending from said blocks at right angles and pivotally connected therewith at their inner ends, the

opposite ends of each adjacent pair of arms 15 termininating in spaced relation, arcuate castings pivotally connecting the free ends of each adjacent pair of arms that are disposed in alinement, rim engaging hooks adjustably mounted in the ends of said castings, and rectangular shaped rim abutting heads pivotally connecting the free ends of the remaining adjacent pairs of arms that are alined.

In testimony whereof I affix my signature.

WILLIAM HUMPHREY BUTTRAM.
